DESIGN FOR A CONTAINER FOR LEAD PENCILS OR THE LIKE

Walther Friedlaender, New York, N. Y., assignor
to Eagle Pencil Company, New York, N. Y., a
corporation of Delaware

Application October 6, 1936, Serial No. 65,177

Term of patent 3½ years

To all whom it may concern:

Be it known that I, Walther Friedlaender, a citizen of the United States of America, residing in the city of New York, State of New York, whose post office address is 710 East 13th Street, city of New York, State of New York, have invented a new, original, and ornamental Design for a Container for Lead Pencils or the like, of which the following is a specification, reference

being had to the accompanying drawing forming part thereof, in which

Figure 1 is a top plan view of the container, and Figures 2 and 3 are perspective views, respectively, of the opposite sides of the container.

I claim:

The ornamental design for a container for lead pencils or the like, as shown.

WALTHER FRIEDELAENDER.
